Harry B. Egleston, Livonia, and Donald E. Smith, Detroit, Mich., assignors to Ex-Cell-O Corporation, Detroit, Mich., a corporation of Michigan

Application March 25, 1955, Serial No. 496,816

11 Claims. (Cl. 118—423)

This invention relates to an automatic conveyor system for loading, transferring, and carrying cartons, and has particular reference to a machine for wax-coating flat-top cartons such as disclosed in application Serial No. 135,430 filed December 28, 1949 by Charles H. Dixon, now Patent 2,730,288, and in Patent 2,663,981 issued December 29, 1953 to R. S. Sanford.

Disposable cartons made of paperboard or other sheet material are well suited for the distribution of milk or other foods when coated or impregnated to render them impervious. The coating, usually applied as a hot liquid paraffin or wax-like substance, must be applied after the carton has been creased and formed, and high production rates also require rapid cooling and hardening of the applied material. The coating must be thorough, inside and out, undamaged by handling. Strict sanitary standards as well as economic requirements dictate a minimum of handling, and complete automation is virtually a necessity. The general aim of the invention is, therefore, to provide a fully automatic machine for receiving erected flat-top paper cartons of the type described, conveying them in timed sequence and predetermined position, and discharging them. It is a more particular aim to provide with such a machine a complete and effective inner and outer cooled moisture-proofing coating for such cartons at a high rate of production.

It is another object to provide a coating machine of the type described which is easy to clean and maintain and fully conforms to the rigorous sanitary requirements that must be met for dairy equipment and similar applications.

It is still another object to provide a high-speed conveyor-supplied coating machine for simultaneously treating several cartons.

It is a further object to economically and efficiently arrange both hot-coating and refrigerating stations for cartons conveyed through the machine.

It is also an important object to provide an improved automatic conveyor system for such a machine.

It is a further object to provide an improved automatic transfer system to convey hot-coated cartons from a coating conveyor to a cooling conveyor.

It is another object to provide improved automatic carton infeed and discharge means for the conveyor system.

While the containers may be filled directly upon discharge from the coating machine, it is sometimes desirable that the coated containers be shipped or held for later filling. This is particularly apt to be the case where the dairy filling equipment does not economically justify the installation and operation of automatic coating machines. In such instances it is desirable that the filling flap be temporarily sealed, so that the coated inner surface remains sanitary. It is, therefore, an additional object to provide a coating machine for automatically closing and sealing the carton opening immediately after application of the coating material to the carton's inner surface.

2

It is a further object in such a machine to provide means for simultaneously transferring a hot-coated container to a cooling system and closing and sealing the flap through which the inner coating was applied.

5 Briefly, in accordance with certain broader aspects of our invention, a coating machine is provided having a hot-dip coating tank and a refrigerated cooler through which a continuous conveyor system is provided. The containers are fed to the machine on a conveyor and 10 automatically loaded in groups on a coating carrier, which grasps the tops of the cartons and holds the top flaps open. The carrier conveys the cartons through the hot liquid coating while maintaining a predetermined angular carton position and without contacting the surfaces requiring coating. A transfer mechanism provides 15 for the transfer of each group of cartons to a cooling carrier, which holds the cartons at the top and conveys them through the cooling unit, preferably including a water tray for cooling each carton base. A discharge 20 mechanism unloads and discharges the completed containers. While the conveyor system circuit is closed for continuous operation and is arranged for use of a plurality of both heating and cooling carriers, the heating and cooling carriers are confined to the heating and cooling units, respectively, for efficient operation.

In accordance with a particular further feature, the transfer mechanism automatically closes and temporarily seals the filling flap in the course of transferring each hot-coated carton from the coating carrier to the cooling carrier.

The objects of the invention thus generally set forth, together with other objects and ancillary advantages, are attained by the construction and arrangement shown by way of illustration in the accompanying drawings in 35 which:

While the invention is susceptible of various modifications and alternative constructions, there is shown in the drawings and will herein be described in detail the preferred embodiment; but it is to be understood that it is not thereby intended to limit the invention to the form disclosed, but it is intended to cover all modifications, alternative constructions, and equivalents falling within the spirit and scope of the invention as expressed in the appended claims.

General organization

Referring now to the drawings, the coating machine 30 shown therein may be functionally described as having a coater unit 31 and a cooler unit 32. The coating unit, which contains a tank of heated wax, is the major left-hand structure of the machine as oriented in Fig. 1; and the cooling unit, which is refrigerated and also contains a water tank, is the major structure of the right-hand portion of Fig. 1. The invention, however, both in its components and in its combination of them, is better reflected by an analysis of the machine in terms of structural units and their particular functions and interaction with the other units of the machine. To this end, and to facilitate an understanding of the invention, the machine is described as an infeed unit 33, a coating loader 34, a hot-coating conveyor 35, a cooling transfer unit 36, a cooling conveyor 37, and a discharge unit 38. These units successively act upon the cartons supplied to them to perform the coating and cooling functions.

The machine is suitably mounted on a sturdy table or base structure 39 with cabinet enclosures for the heated coating and refrigerated cooling zones. A timed drive system 40 actuates the overall conveyor system, a main drive electric motor being suitably mounted on the coating cabinet enclosures.

In the particular embodiment described, the cooling transfer unit 36 also functions to close and seal the filling flap of each carton so that each carton may be stored or shipped in a sanitary condition for subsequent use.

An example of the type of carton employed is displayed in Fig. 15, this carton 41 being commonly employed for milk and known in the trade as a flat-top paper carton. One of its distinguishing characteristics, at least so far as the present invention is concerned, includes a flat-top closure 42 with the upper portions 43 of a pair of opposite sides bent inwardly and folded just under the flat top of the carton so that the carton top has at least one pair of overhanging marginal ledge portions 44.

A filling flap 45 on the top of the carton is bendable upward as shown in the drawing, and is provided with a glue-coated area so that it can be finally sealed permanently in place after the carton is ultimately filled through the top opening under the sealing flap. This opening also provides access for the coating material, usually paraffin, to the inside of the container during the coating process. A tab 46 is pulled by the ultimate consumer to open a pouring aperture in the carton.

For reference in following the detailed description, the filling opening may be considered as at the back or rear portion of the flat top 42, and the pair of top overhanging portions 44, significant with respect to the coating

machine operation, may be defined as the top sides of the carton. The tab 46 is by this nomenclature at the front of the carton.

The formed cartons are supplied from a suitable source, such as forming or erecting machines of the type described and claimed in co-pending applications Serial No. 318,882, filed November 5, 1952 of James F. Earp, now Patent 2,770,175, and Serial No. 319,684, filed November 10, 1952 of Charles Z. Monroe and James F. Earp, now Patent 2,745,323, both of which applications are assigned to the assignee of the present invention. These both represent machines having a high production rate, and with which a coating machine of the type herein described is economically employable.

The structure of the carton described, with its converging upper side walls 43, provides a reinforced upper sealing surface against which the top closure can be pressed with suitable force to complete the carton enclosure when the carton is filled. As brought out in the following detailed description, the same overhanging margins or ledges of the container are utilized to safely and securely grasp and convey each container and transfer it through the operational steps of the coating machine. It will also become apparent that the conveying and transferring means are simple and direct, without damaging the carton or its coating and without preventing complete coating and cooling of all of the carton portions which must be rendered impervious to the ultimate carton contents.

Carton infeed unit

At the infeed end of the coating machine the infeed unit 33 is mounted to receive cartons to be coated from a conveyor 50 and to release them one by one to a timed gate 51 of a rotary carrier 52. The carrier transfers the cartons with a positive feed to the infeed chute of the coating transfer or loading unit 34. A tab breaker 53, as an auxiliary apparatus operated by the infeed unit rotary carrier, tucks in each carton tab 46 to assure its final position prior to coating.

The infeed conveyor itself suitably comprises a moving belt 54, suitably in the form of an articulated series of metal plates, upon which the cartons 41 to be coated are placed in an upright position. Guide rails 55 and 56 constitute what may be termed the front and back rails, respectively. The conveyor leads to a stationary plate or platform 57, positioned at the entrance to the rotary carrier 52. The conveyor itself may be suitably driven by any separate conveyor drive motor and need not be synchronized with the conveyor drive 40 of the coating machine.

The conveyor loading requirements are simple, the cartons being simply placed upright on the conveyor with their front tab sides forward. This assures, without further adjustment or sorting, that the carton will be in the proper position for further automatic operations. The spacing between the cartons placed on the conveyor belt is not critical. The cartons will align themselves in a closely filed array behind the front carton on the platform 57, since the front carton is restrained from advancing until the cumulative thrust of the cartons on the moving conveyor behind it is sufficient to provide quick and sure loading.

The rotary carrier to which the top cartons are conveyed consists essentially (see Fig. 4) of a hub or collar 58 keyed to the vertical rotary shaft 59 of the infeed unit and having a plurality of radially extending pusher fins or paddles 60. In the particular embodiment illustrated the paddle wheel so formed has four sections, and thus four paddles equally spaced and each defining a carton carrying position in front of each paddle. Each paddle also includes an inner flange or stop 61 defining the minimum radial spacing of the carton from the paddle wheel axis and extending in the direction of rotation. Since the paddle wheel direction is in this case counterclockwise as viewed from the top (Figs. 2 and 3), arcuate bottom

and outer side rails 62 and 63 extend along a portion of the circular paddle path from the infeed conveyor to the infeed chute of the coating loader unit. The side rail 63 may simply be an extension of the rear guide rail 56 of the conveyor. Each carton, as it is pushed into the path of one of the paddles by the cumulative thrust of the cartons on the conveyor behind it, is thus conveyed along the arcuate path by the rail carrier to the infeed chute. The carrier shaft 59 is timed to deliver the cartons to the infeed chute at a rate synchronized with the coating machine conveying system. This is simply accomplished by coupling the shaft 59 to the conveyor drive system 40. As shown in Fig. 4, a bevel gear 64 at the lower end of the shaft is engaged by a second bevel gear 65 driven by a link chain from sprockets linked to the coating conveyor chain.

In order to regulate the entrance of the cartons to the paddle wheel, the gate assembly 51 is placed in the path of the front carton of the platform 57. The gate has a pressure-responsive blocking latch 66, which blocks the front carton unless enough cartons are aligned in the file behind it to assure its movement into the paddle path. A second function served by the gate is provided by a pusher arm 67, actuated in synchronism with the paddle wheel rotation, for moving the leading carton to clear the blocking latch when the carton pressure on the latch is sufficient to release the pusher arm.

Referring to the gate mechanism in further detail, the latch 66 comprises a lever, pivoted at one end 68 for horizontal movement and having its other end extended as an upright finger 69 within and near the front rail of the conveyor, to block the further passage of the leading carton. Actually, the conveyor guides 55 and 56 are spaced sufficiently far apart to allow a small lateral displacement of the carton beyond the upright finger 69 near the front guide of the conveyor except for an auxiliary back rail having a converging portion 70 which biases the leading carton against the front rail. The pressure finger 69 is movable forward, however, against the pressure of an adjustable compression spring 71 to a limit stop position 72. When several cartons are on the conveyor behind the leading carton, their cumulative thrust afforded by the small traction of each of the like containers displaces the latch finger 69 against the bias spring 71 to the stop position. The forward displacement of the front carton is also enough to allow it to clear the end of the converging back rail 70, so that the carton, if moved laterally toward the back rail 56, is in a position to be advanced by the cartons behind it into the paddle-wheel path.

A pusher arm 67, which laterally displaces the cartons, is mounted on a pivot 73 and has a cam-following extension 74 with an end roller 75a which rides a four-lobe cam 75 mounted on the paddle-wheel shaft 59. Any suitable biasing means, such as a helical torsion spring mounted on the pressure arm pivot 73, may be suitably employed to urge the cam-following arm of the pusher against the cam. When the cam follower rides a low portion of the cam at a time corresponding to the approach of a paddle 60 to the platform 57, the pusher arm 67 moves toward the side of the front carton. A shoe or plate 76 at the end of the pusher arm then extends within the front conveyor guide 55 to displace the front carton laterally beyond the pressure finger, providing the finger has retreated against its spring force by the carton pressure. A back edge portion 77 of the shoe engages the corner of the next carton as the next carton moves forward to push the laterally displaced front carton into the path of the oncoming paddle 60. Fig. 3 illustrates the lateral displacing action of the pusher arm.

As the pusher cam follower 74 rides a high portion or lobe of the cam 75, the pusher arm 67 and its shoe 76 are retracted from the carton head to the position shown in Fig. 2. When this happens, the latch finger 69 is no longer

restrained by the forward edge of the shoe 78, nor by the laterally displaced leading carton, and is hence free to be biased by spring 71 back to the original latching position. In such a position the finger 69 moves in front of the pushing face of the shoe 76 in its latching position, disabling the pusher arm. At the same time the second carton, no longer restrained by the back edge 77 of the now retracted shoe, continues to move forward, completing the advance of the slightly laterally displaced leading carton. The second carton comes to rest finally against the finger 69 of the blocking latch 66, while the released carton is conveyed along the arcuate guide 62 and 63. The former second carton then must repeat the procedure of pushing the finger 69 of the blocking latch forward so that it clears the end of the converging rail section 70 and is in a position to be laterally displaced by the shoe of the pusher arm when that arm is cam actuated in synchronism with the approach of the next paddle.

In the event that the number of cartons behind the leading carton is insufficient to build up enough thrust behind it to push it forward against the latch spring pressure, the shoe 76 of the pusher arm remains behind the finger and is thus latched out of operation. In this position (Fig. 2) the pusher cam-following arm 75 is held back against the pressure of its bias spring and disabled from following the low portions of the cam 75. In this way the gate regulates the carton feed, so that the risk of jamming due to slow carton movement into the paddle wheel path is minimized.

It may be seen that, since the paddles do not enclose the cartons, the cartons are free to follow the tangential extensions 80 of the side and bottom rails 62 and the new front rail 81 at the exit or unloading zone of the paddle wheel adjacent the end of the chute of the coating conveyor loader.

The paddle-wheel drive thus constitutes a positive feed for the cartons, and the pressure required to load the cartons into the paddle wheel is simply that traction or friction thrust derived from the empty cartons resting on the conveyor belt and aligned behind the lead carton. The pressure, as is apparent from the foregoing description, is readily predetermined for a minimum operating value by adjustment of the clutch finger spring 71. There is, of course, a desirable limit to the positive paddle-wheel feed, to prevent crushing of cartons in the event of jamming in the paddle wheel or somewhere ahead of it in the conveyor system. For this purpose the assembly of paddles 60 may suitably be held stationary with respect to the hub 58 by spring-biased detent pins 83, which are displaced when the jamming torque on the paddle 60 causes the pins to be forced out of engagement. A follower lever 84 may be suitably employed to help transmit the motion of the pins under these conditions to actuate a switch 85 in the conveyor shut-down or trouble-indicating circuit.

Also shown as auxiliary equipment is a tab breaker 53, which may be advantageously employed with the rotary infeed unit to take advantage of the predetermined carton positions and the timed drive of the rotary unit. The tab 46 extending from the front of the carton is bent down and under the leading top-side overhang 44 as a final step in preparing the carton for coating, or for at least assuring that the tab has not slipped out of place prior to the coating.

As may be seen in Figs. 2 and 4, an operating lever 88 oscillates on a pivot 89 above the front discharge rail 82 leading away from the paddle wheel to the loader infeed chute. One end 91 of the lever follows a cam 90, suitably mounted for rotation on top of the rotary carrier 52 of the infeed unit. As shown, this cam is suitably bolted to the top of the carrier hub assembly 58. A spring 92 keeps the cam-following end of the lever 88 biased against the cam. The cam itself has four lobes, preferably in the form of abruptly projecting teeth hav-

ing a relatively small angular span in order that the folding or breaking action may be quickly completed.

The lever motion is transmitted through a floating pivot linkage 93 to a pressure finger 94 on a fixed pivot 95. The bar 96 at the end of the pressure finger 94 bears against the tab surface to fold it inwardly, the motion being transmitted to it by the rise of the cam-following end of the lever 88 over the high points of the cam 90. It will be appreciated that, while the paddle wheel does not directly place the cartons under the tab-breaking mechanism directly from the paddle wheel, each carton is given a definite position on the bottom discharge guides 80 between the front rail 82 and the back rail 81 as the end of each rotating paddle 60 leaves the carton. The carton is then advanced by successive carton widths due to the positive placement of additional cartons behind it. A spring detent 97, suitably extending into the carton path, admits the cartons to the chute but prevents them from back-sliding after the paddle has advanced beyond contact with each unloaded carton (see Fig. 3). Reference is also made to our copending application S. N. 496,452 filed March 24, 1955 and assigned to the same assignee where carton infeed mechanisms suitable for coating machines are disclosed and claimed.

Coating loader unit

In the loader unit 34 a chute 100 is provided to receive cartons fed to it from the infeed unit 33, the cartons being kept in closed file by a compacting or ramming means 101. A rake-like means 102 selects for loading cartons spaced from each other by the width of intervening cartons, and a timed rake-drive mechanism 103, synchronized with the coating conveyor drive, provides the rake motion at the correct instant and velocity to overtake and load the plurality of cartons into a moving carrier of the coating conveyor.

The chute 100 is horizontally disposed and aligned with the carton discharge guides at the exit from the rotary infeed mechanism to extend across the infeed end of the coating machine (Fig. 5). In this instance it is designed to accommodate 12 cartons side by side, the cartons sliding on the floor 105 of the chute toward its end as they are fed into the chute by the rotary unit 52. A front wall or rail 106 retains the cartons in line and is provided with vertical slots 107 to permit the passage of rake fingers transversely across the chute from the front. It will be noted from the drawings that two such vertical slots are provided at intervals corresponding to every other carton width along the chute wall 106. The back wall of the chute is not continuous, but, instead, spacer members or blocks 108 are employed, each the width of the carton and spaced from each other by carton widths. The spacer blocks have front surfaces which help to confine the column of cartons within the chute by restraining alternate ones, the front surfaces having rounded corners to prevent the jamming of cartons as they advance into the chute. The short transverse slides 109, defined between the alternate spacer blocks, extend rearwardly from the chute or toward the interior of the coating unit. For convenience, the floor of this part of the chute may be termed the apron.

The cartons when loaded into the chute push back a sliding stop 101, which slides in a groove 110 in the chute floor 105. To provide enough resistance so that the cartons will be pushed in even file against each other, the stop is biased toward the input end of the chute, the cable 111 running along the sliding stop groove 110 and over a pulley 112 (Fig. 3) to a suspended weight suitably housed in a vertical cylinder 113. The descent of the weight is preferably cushioned, as by a conventional dashpot arrangement, so that the stop 101 will not unduly accelerate in retreating toward the infeed end of the chute upon removal of the cartons. The end detent 97, previously referred to, prevents the cartons from being pushed backwardly out of the chute by the biased stop

in the intervals between the periods of applied pressure by the advent of additional cartons on the paddle-wheel carrier.

5 The rake-like selecting means 102 by which alternate cartons are pushed from the chute onto the spaced apron sections 109 between the spacer blocks 108 has a plurality of pairs of spaced vertical fingers or bars 115. These are supported on the transverse bar 116 extending the length of the loading chute, and have an arcuate end support member 117 at each end. To each arcuate support member are connected the front and back pivots 118, which are horizontally aligned when the rake is held in a vertical position.

10 Referring to Fig. 6, the selector rake drive 103 on the coater unit cabinet may be seen to comprise essentially a front and rear link chain loop 119 positioned above each end of the chute 100. Each of these carrier loops extends between upper and lower chain sprockets 120 and 121, respectively. As further shown in Fig. 8, the sprockets 20 are driven at the same rate on the rear side wall 122 of the coater cabinet, each suitably having a pinion 123 which is driven by the rotation of the common gear 124. The gear shaft is part of the drive system 40, being suitably coupled to the coating conveyor. Any suitable 25 means, such as the adjusting blocks 125, may be employed to maintain the tension of each chain loop 119.

30 In order to provide the desired motion to the rake assembly, the front and back carrying pivots 118 at each end of the rake are connected to corresponding links of each front and back rake carrying chain 119, connecting links 126 being shown for that purpose. Since the connecting links 126 must always be horizontally aligned, the rake fingers 115 themselves always remain in vertical position. The selector rake will thus move downward 35 from the top of the rake carrier chains and in front of the loading chute until the rake reaches the bottom sprocket 121 of each chain. At that point the rake will move inwardly, that is, toward the inside of the coating cabinet, to push alternate cartons in front of the various 40 pairs of rake fingers onto the infeed chute apron. The transverse displacement of each carton is predetermined by the rake conveyor 119, the rake fingers 115 rising with the vertical or near-vertical run of the respective chains as the rake chain connecting links 126 finish their travel 45 around the lower sprocket 121. Preferably, the upper and lower chain sprockets 120 and 121 are not quite vertically aligned; instead, the top sprocket is somewhat closer to the infeed edge of the cabinet than to the lower sprocket. Guides 127 for the rake pivot ends are similarly 50 aligned. This assures that the rake fingers 115 will pull away quickly from the cartons as the rake is elevated. A hand wheel 128 on the front coater cabinet wall (Fig. 9) is provided for manual operation or setting of the rake. A 55 ratchet or clutch 130 is provided between the rake drive gear 124 and its drive sprocket (Fig. 8) to permit such adjustment.

60 While the further operation of the loading unit may be better understood in connection with the description of the coating conveyor, reference is made to Figs. 10-14 for the operation of the loading mechanism thus far described. Thus, referring to Fig. 10, the infeed chute is indicated as filled with cartons bearing the numbers 1-13. The rake fingers 115 at that instant are directly in front of the cartons and in their lower position. Since the paddle wheel and the rake assembly are chain-driven from the same drive system 40, they are synchronized with each other. The rake makes its appearance in front of the carton stack when the chute is loaded (provided a sufficient supply of cartons is maintained at the infeed mechanism) and also during the interval when the stack is not being advanced by an added carton. Fig. 11 shows alternate or odd-number cartons being pushed by the rake fingers onto the chute apron sections to overtake the holders 131. Fig. 12 shows the completion of 70 this motion, the holders being loaded by the respective 75

cartons and the rake teeth ready to begin their vertical ascent. During that interval the sliding stop has moved toward the infeed end of the chute pushing the spaced remaining even-number cartons before it to a stack representing a half-filled chute. Fig. 13 shows the chute loaded again and the rake fingers in a position to again move forward. During this time the loaded carriers have moved away and a new set is approaching loading position. Fig. 14 shows the rake fingers as having loaded a second set of six alternate cartons into the second set of holders. It may be seen that the loading action repeats, six cartons at a time (if the carton supply is adequate), into the continuously moving holders.

Coating conveyor

A plurality of carrier bars 130 extends transversely inside the coater unit 31 of the machine to convey the cartons through the coater, each bar having a plurality of individual holders or hangers 131 which grasp each carton by its top side ledges 44, the only part of the carton where the coating requirement is not critical. The holder closing mechanism 132 closes each hanger to keep the carton in place. The conveyor chain circuit 133 (Fig. 1) on each side wall of the coater cabinet provides a path for the carrier bars on the loader through the coater unit and back to the loader after removal of the coated cartons. Adjacent one portion of the conveyor circuit is a wax tank 134 in which the cartons are submersed to receive a wax coating. Means are provided to maintain the cartons at particular angles to allow the free flow of wax through the filling opening and also to permit draining of surplus wax. This means preferably takes the form of cam-following crank 135 on the carrier bar ends and cam surfaces 136 on the coater unit cabinet adjacent to the conveyor chain circuit.

Referring to the conveyor in more detail, each carrier bar 130 is suitably made of sheet metal stock with a bent-up reinforcing rib 137. Six spaced hangers or holders 131 on the underside of each carrier bar are aligned to receive alternate cartons from the chute 100 of the loader unit 34. These holders are suitably made of a sheet metal bracket 138, having a central portion welded or otherwise secured to the carrier bar and with side edges bent downwardly and inwardly. An upstanding runner 139 on each inner flange of the bracket 138 provides a small area surface for supporting the carton ledges 44. A second set of runners or cams 140 extends downwardly from the carrier bar against the top of the carton supported on the runners 139. The upper runner decreases in its vertical dimension in the front portion of the holder so that the top flap 45 of the carton is folded back to an acute angle with the carton top, without being forced flat. The rear surfaces of the runners are provided with closure stops 141, which prevent the cartons from passing out of the rear side of the holders.

To retain the cartons in the holders 131 a closure mechanism, including a finger 143 with a downwardly extending tip, extends over the top front edge of each carrier. A pivoted shaft 144 for oscillating the fingers is provided, one shaft being suitably employed for each two fingers 143. A torsion spring 146 biases the shaft and closing fingers into the closed position. In order that the fingers 143 may be lifted during the loading of the carton holder or hanger 131, a cam-following lever or operator 145 extends frontwardly and downwardly from each finger shaft 144 at a position on the carrier bar between the holders. This lever is proportioned to be raised by a projecting cam surface 147, which extends upwardly from a chute block 108.

It will be understood from the description of the loading mechanism previously set forth that, when a carrier bar 130 rides upon the chute aprons 109 at periodic intervals, each cam follower 145 strikes a cam 147. Each finger 143 is thus lifted for a portion of the carrier travel so that the carton side ledges 41 can slide into the

holders. As best shown in Fig. 7, the already partially open top flap is bent back further as the carton is pushed further into the holder. A pushing action is provided by the loading rake 102, previously described, which travels faster than the carriers 131 to overtake them. When the carton is pushed all the way into its holder, the loading fork moves upwardly away from the carton. The carrier bar 130 will have then moved past the cam 147 so that the cam-following lever and the holding finger 143 are spring-biased downwardly again. This closes the carton holder, and the carton cannot slip out in either direction. It will be noted that, while the holder itself is closed, liquid access to the top of the carton and the carton opening is permitted.

15 The path of each carrier is controlled by the conveyor circuit 133, movement of the carrier past the loading chute being only one part of the continuous carrier chain circuit. Two link chain loops 148 are provided, one on each side wall of the coater cabinet; and an axially extending pivot shaft 149 at each end of the carrier bar is pivotally attached to a chain, the bars being spaced at equal intervals around the conveyor circuit. A guide roller 150 is provided on one end of one of the pivot shafts.

20 25 As may be seen most easily in Figure 1, where the conveyor chain circuits are shown, the path of the chain of the hot-coating conveyor is defined by a plurality of sprockets 151—161. Starting with sprocket 151 at the beginning of the loading cycle, the chain extends horizontally to sprocket 152 and then down into the coating tank 134 over sprocket 153. It next passes horizontally under the sprockets 154 and 155 below the level of the melted paraffin 162 or other moistureproofing material which has been heated to a liquid state. The chain then continues up vertically over sprocket 156 and under sprockets 157 and 158, which are associated with the unloading station of the cooling transfer unit 36. The circuit continues through the upper part of the coating cabinet over sprockets 159, 160, and 161 to return the empty carriers to the sprocket 151 again.

30 35 An appreciation of the number of cartons that are simultaneously accommodated in the coating machine may be derived from the fact that in an actual apparatus such carrier bars, each having six hangers, are evenly spaced on the conveyor chain circuits.

40 45 A groove 163, formed between abutting surfaces on the inner front side wall of the cabinet and aligned with the adjacent conveyor chain, provides a path for the roller 150 on one end of each carrier. This permits free pivoting of the hangers and, without additional control means, the cartons would hang freely downward or swing with the movement of the conveyor carrier bars.

50 55 It is important, in accordance with one aspect of the invention, that the angular position of the cartons be controlled as desired during different parts of the conveyor path. Each conveyor carrier bar therefore has at its other end beyond the pivot shaft 149 a triple crank cam follower 135. This cam follower has what may be termed a major crank arm 164 at the end of the carrier bar beyond the chain. A relatively long roller 165 at the end of the crank arm serves as a cam follower. When this roller is cammed to either side of the path of the carrier bar pivot (this path being that of the conveyor chain 133), the angular position of the carrier with respect to the chain is thus also changed. To provide positive and complete angular control without necessitating reliance upon gravity or on larger camming force components on the carrier and drain, two additional crank arms are employed. The two crank arms, which may be termed as auxiliary to the center or major crank arm, extend from the carrier shaft 149 in opposite directions: one as a first auxiliary crank arm 166 with a medium length cam-following roller 167, and the other as a second auxiliary crank arm 168 with a short cam-following roller.

169. The different lengths of the rollers permit their selective engagement by the cams.

The carrier cam guides 136 upon which the crank arm rollers variously ride are shown in Fig. 18, which represents a view of the inner surface of the back side wall of the coating conveyor. The carton position (that is, its angle with respect to a tangent to the conveyor path at the carrier pivot) is shown by the dotted outline of the cartons at several of the various carrier positions. Figs. 19 and 20 further show selected cam details and the position of the triple crank arm 135 and the holder 131 at selected portions of the path. A brief description of the operation of the cams shown in these figures is sufficient to illustrate the construction and function.

Thus, in portion (a) of Fig. 19, the conveyor path is downward near the sprocket 161. A cam surface, suitably provided by an upstanding flange 170, extends parallel to the conveyor path. Both the long and medium rollers 165 and 167 ride on the cam 170 to thus determine the position of the holder 131. Another cam 171 (shown in part (b) of Fig. 19) confines the long roller 165 between it and the first bracket 170. The long roller 165 is thus confined under the bracket so that it leads the shaft in the conveyor direction. A lower cam or guide 172 confines the long roller 165.

In part (c) of Fig. 19, a cam plate 173 is provided which has an upper groove 174 as a continuation of the roller path between cams 171 and 172. This groove continues past the conveyor path around the initial sprocket 151, and then retreats on itself to diverge downwardly in a second groove 175. The long roller in following this groove continues toward its end, and then reverses to follow the lower groove 175. In this way, the holder 133 is held generally downward on both the upper and lower runs around that sprocket. The rotation of the carrier is continued, the short roller 169 bearing on a bottom guide of the cam plate 173. The medium roller 167 is thus brought to bear around the upper edge of the lower groove 175 as part (d) in Fig. 19. An arcuate groove extension 176 of the lower groove 175 rotates the carrier as it proceeds further to bring the holders from their vertical position.

In Fig. 20, where the conveyor path is around the wax tank sprocket 154, it may be seen that the cammed path for the long and medium rollers 165 and 167 is provided to keep the carton almost horizontal as the carrier approaches the sprocket. In order to maintain this position as the carrier travels around the sprocket, not only is a path 178 provided for the long roller, but separate paths 179 and 180 are provided for the medium and short rollers 167 and 169. It will be seen that the torque on the major crank arm 164 exerted by the carrier and its load would be enough to require very precise cam positions were the major crank arm alone to be employed. However, the use of the auxiliary crank arms provides a more effective torque for turning the triple crank arm as it rounds the sprocket 154. The operation is similarly advantageous in other portions of the camming system, and, instead of the crank arm roller applying its torque directly with respect to the unanchored pivot of the carrier, it is applied with respect to one or both of the more easily guided other crank arm rollers.

With the carton angle thus determined, the advantages of the carton top holding conveyor in controlling the wax coating can be realized. As may be particularly readily seen in Fig. 18, the cartons approaching the initial sprocket 151 from the last sprocket 161 on the conveyor chain are desirably carried downward so that they will not interfere with the operation of the loading rake. As required for the loading, the cartons must also hang vertically downward as they pass through the loading zone along the horizontal conveyor run between sprockets 151 and 152. The cartons, in descending into the wax bath, are then swung upwardly toward a generally horizontal position. More precisely, the leading or closed end of

the carton is disposed downwardly a few degrees below the horizontal as the carton descends into the molten paraffin, the bottom surface leading in the direction of travel through the wax bath in the horizontal run between the sprockets 154 and 155. Under these conditions the opening for filling is in the uppermost portion of the carton, and the air in the carton is free to escape. Trapping of the air is thus avoided, it being important, of course that all portions of the carton, inside and out, representing paperboard in contact with the ultimate carton contents, be thoroughly coated. It will also be appreciated that in pushing the cartons bottom end first through the wax, the cartons must also be firmly held against upward rotational movement of the carton bottoms. In order to drain the wax from the carton, the cartons rise bottom end first from the liquid wax. The angular position is preferably somewhat less than vertical, the camming surfaces providing such a position to accumulate some of the draining wax on the tab portion of the inner side of the carton top. This is a desired objective to assure adequate sealing around the pouring aperture. The carton drains while it is in this nearly vertical position. The vertical run is maintained for a substantial vertical distance in order to permit sufficient drainage time, the drained wax thus returning directly to the tank. After draining, the cartons are again suspended in the vertical position which is necessary for the carton transfer in the transfer unit 36.

Transfer unit

The transfer or cooling loader unit 36 is provided to remove hot-coated cartons from the coating conveyor loop and to transfer them to the cooling conveyor loop. During the transfer the top flap 45 of each carton is closed to temporarily seal the carton and maintain its sanitary condition. A stationary guide assembly 181 is stationed between the coater cabinet and the cooler cabinet to provide a top holding slide or hanger for each of the cartons during the transfer operation. This assembly includes a stripping station 182, where the cartons are removed from the coating carriers, and a cooling conveyor loading station 183 for loading the cartons in the cooling conveyor carrier with the top flaps still closed. A short high-speed conveyor 184 carries the cartons along the stationary guide 181 from the stripping station to the loading station.

Referring to Figs. 21 and 22, the stationary guide 181 is supported by a stationary transverse support bar 185 between the horizontally aligned sprocket 158 of the coating conveyor and the sprocket 186 of the cooling conveyor. These sprockets represent the end of a horizontally loaded coating conveyor run and the beginning of a horizontally loaded cooling conveyor run. Held by the support bar 185 is an array of spaced support blocks 187, which define recesses between facing surfaces 188 of adjacent blocks for the conveyor carton holders and upper portions of the cartons. Inner shoulders or guides 189 on the facing block surfaces are spaced to support the carton ledges 44, so that the cartons may slide across the guide 181.

When a coating conveyor holder 131 enters one of the recesses 188, the carrier closing finger 143 and cam follower 145 must be lifted in order that the carton may slide out of the holder. Accordingly, a cam 190 is mounted on a support block 187 in the path of the cam-following actuator 145 of each carrier bar. The cam has a first lift section 191, which raises the pivoting closing finger 143 sufficiently to allow the carton to slide partially out of the holder. In this position the lower edge 143 of the finger catches the edge of the carton filling flap 45. As the carrier proceeds further along the guide, a higher portion 192 of the cam lifts the carrier finger higher. As soon as the finger edge 143 is effectively hooked over the flap edge, the flap is raised with the finger. A further forward motion of the carton carrier or hanger 131 brings

the carton flap to a more upright position and then over towards its closed position. At a further position of the cam-following operator 145 the carrier descends on a depressed surface 193 of the cam 190. The carton top flap is forced down by the descending finger 193 to its closed position, thus closing the filling opening through which the wax for coating the carton interior was supplied.

A stop or stripping pin 195 is provided at each side 188 of each recess below the guide flanges 189. These pins block the further advance of the carton during the portion of the coating conveyor run in which the carrier closing finger 143 is actuated to fold the top flap toward a closed position. When the carrier 131 is advanced beyond the stripping pins 195, the carton is completely removed from the holder, although the trailing finger 143 still biases the top flap edge downward. Since the carrier is necessarily positioned above the guide surfaces 189, the carton upon removal drops so that its overhanging ledges or margins rest on the stationary guide surfaces 189. This vertical displacement also clears the cartons of the stripping pins, inasmuch as a narrower portion of the carton between the oblique panels 43 is positioned between the pins. The carton is thus free to be moved forwardly. The empty coating conveyor carrier 131 proceeds around and up the sprocket 158, a final high portion 194 of the cam 190 lifting the closing finger 143 for a safe clearance.

While the empty or stripped carrier 131 proceeds above the guide assembly 181, the stripped carton 41 is independently conveyed along the guide flanges or shoulders 189. A closing cam 196, positioned immediately above the carton, both prevents the filling flap from springing open and keeps it in the desired closed position. As the carton is advanced along the slightly raised portion 197 of the slides toward the loading station, an intermediate sealing cam plate 198, provided with a heater means 199, heats the flap sufficiently to assure that the paraffin is softened to form a wax seal when the carton top cools. As the carton proceeds to the end of the guides and under the end of the hold-down cam 200, the filling flap slides into an open cooling carrier similar to the coating carrier. This carrier, on arriving on the cooling conveyor chain around the sprocket 186, passes the loading station and has its closing finger opened by a lift cam 201 stationed above the slide. After the carton has overtaken the cooling carrier, the further slower advance of the carrier cam 201 causes its closing finger to operate and hold the carton in place.

In order to transfer the cartons between the stripping and loading stations 182 and 183, a relatively fast intermediate conveyor 184 is employed. This conveyor has a chain loop 202 suspended between horizontally spaced sprockets 203 and 204 near the stationary guide ends. The upper run of the chains is positioned somewhat below the stationary guide to carry a pivoted carrier bar 205 between them. The suspended cartons from the stationary guide assembly are in the path of the bar. To engage the cartons a pusher plate 206 is spaced ahead of the bar at each carton position by an arm 207. The conveyor sprockets are timed with the coating and cooling conveyors, being operated from the same drive system 40. The intermediate conveyor is thus accordingly timed, although it has a faster linear speed, so that its pusher plate picks up a carton just after it has been stripped out of a coating carrier by the pins 195, and pushes it transversely across the guide assembly to overtake a cooling conveyor or carrier just as that carrier is passing through the loading station.

The angular position of the transfer conveyor bar may also be controlled in the manner provided for the coating conveyors. Thus, the conveyor bar 205 may be provided at one end with a triple crank cam follower 208, similar to that of the coating carrier, which is cammed to a desired angular position by a stationary camming assem-

bly 209. This is most useful at the end of the conveyor run, at which point a pusher plate 206 may be cranked backwardly in order that the forward pushing motion may be abruptly terminated as the conveyor bar drops vertically around the sprockets 204 and thus out of engagement with the cartons.

It will be seen that not only are the cartons unloaded from one conveyor and automatically transferred to a second conveyor, but the filling flap is also sealed during this step. The same mechanism employed for closing the carriers and holding the cartons open is also employed to complete the flap closing operation.

Cooling conveyor

In the cooling conveyor 37 the hot-coated cartons with their tops sealed are loaded from the transfer unit in the cooler carriers 211 on carrier bars 212. A chain circuit 213 is provided on both sides of the cooling cabinet interior. The conveyor path runs through a water tray 214 in the bottom of the cooling unit so that the carton bottoms may be quickly chilled. A refrigerating apparatus 215 is included to provide a chilled zone for the timed carton travel in the cooler cabinet.

The cooling carrier bars 211 and their associated hangers 212 correspond in construction to the coating conveyor bars and hangers 130 and 131. Likewise a triple crank cam follower 216 and cams 217 for determining the angle of the suspended cartons similar to the follower 135 and guides 136 of the coating conveyor are also employed. A carrier closing finger and operator lever 218 and 219 correspond to elements 143 and 145 of the coating carriers.

The conveyor chain loop extends over sprocket 186 at the transfer unit and sprockets 220 to 229 and is driven in synchronism with the coating conveyor. As may be seen in the initial portion of the conveyor run following the loading of the cartons, the cartons are brought to the bottom portion of the cabinet and suspended in a vertical position while the bottom portions of the cartons are carried through cooling water in the bottom tray 214. This immediately cools the most critical portion of the carton without involving contact of the carton bottoms with the tray or the conveyor. The conveyor then crosses back and forth across the length of the cooler unit as it ascends the cabinet so that the cartons are exposed for a given time to the refrigerated air in the cooler, the cartons being suspended vertically downward. Inlet and outlet ducts 230 and 231 at the top of the cooler unit cabinet circulate the low temperature refrigerant through the heat exchangers 233. Blowers 235 are driven by the motors 236 to circulate the air in the cooler unit cabinet.

Since the carton hangers are of the same construction as employed for the coating conveyor, the cooling air has free access to the top portion of the carton where the carton is held, and at no critical point is the coating damaged or removed. The significance of the cooling operation will be appreciated in connection with the operation of a practical embodiment in which the cartons enter the cooler unit at a temperature of 170° F. and are refrigerated in a 55° atmosphere to a discharge temperature of less than 80° F. It will be seen also that, while the conveyor system is completely synchronized throughout the entire coating machine, the use of separate coating and cooling conveyor loops avoids the problems associated with wax removal when the coating conveyor itself passes through the refrigerated zone.

After the cartons are cooled, they are brought out on a loop of the cooling conveyor through a rear opening of the cooler cabinet to the discharge unit 38. This portion of the conveyor circuit 213 includes a first vertical run downward over sprocket 226 to sprocket 227 and a second vertical run upward from sprocket 227 to sprocket 228. A hood 236 covers the upper part of the discharge loop and an additional hood 237 shields the lower part 75 of the loop around the sprocket 227. The carton car-

rier bars 212 are cammed to hold the cartons horizontally during the downward run to facilitate discharge operation, the camming arrangement being shown in Fig. 24.

Discharge unit

At the discharge end of the cutting machine (Fig. 23), the cartons descending on the cooling conveyor are stripped from their various holders by a stripping mechanism and lowered from a transfer holder to a discharge conveyor belt 242. The cartons are placed on their sides rather than upright on the discharge belt to avoid toppling or dropping of the light weight cartons on the conveyor belt.

A transverse support bracket is positioned across the end of the cooler unit extending outwardly from the rear wall of the unit toward the descending conveyor run and in the path of the horizontally held cartons. The conveyor belt 242 has an upper horizontal run in the path of the descending cartons across the rear of the machine to a sheave 244 on one end of the bracket. The conveyor suitably extends directly to a further processing station for the discharged cartons. No particular conveyor timing is needed, it being only required that the conveyor belt travel fast enough to remove the cartons as they are discharged.

To release the cartons from the carriers a cam 244 is connected to the bracket 243 with a horizontal pivot 246. One cam is provided in the path of each carrier finger operator 219. When a carrier bar 212 passes the cam, its cam operator 219 strikes the upper end of the cam above the pivot and the finger 218 is lifted to open the carrier 211. While the cam is itself pivoted, it has a limit position. The carrier bar 211 itself rides against the cam surface as the carrier descends.

To provide a stop for the cartons so that they may be stripped from the holders, a pair of spaced parallel transverse bars 247 positioned on the ends of a bracket 248 intercept the underside of the horizontally aligned cartons near their top and bottom ends. The bars also constitute a receiving platform for the cartons, the cartons resting on the platform as the open carton carrier proceeds downwardly. Since the platform is designed to hold the carton so that it does not touch the moving conveyor while the carton is in the course of being removed from the carrier, a lifting mechanism for the platform is employed. For this purpose, a first lifting lever 249 is free to oscillate on a pivot 252. One end of the lever is pivoted to the platform support bracket at 253. A lower parallel lever 254 provides rectilinear motion. It has a lower pivot 255 vertically below pivot 252 of the lifting lever and is also pivotally connected at 256 vertically below the pivotal connection 253 of the bracket of the upper lever.

To lift the platform, an extension 257 of one of the cams 245 extends below its pivot 246 and rides in a groove 258 in the end portion of the lifting lever 249 extending beyond the pivot 252. So long as the cam 244 is restrained by the carrier bar or its cam operator, the lower pivoted cam end 257 cannot slide toward the lift lever pivot 252. The lever end thus cannot rise and the platform cannot descend. A return cam surface 259 extending into the path of the conveyor carrier bar below the cam pivot 246 is forced inwardly by the carrier bar when it leaves that lower position. The upper portion of the cam 245 will then be no longer restrained from pivoting outward. With the resulting movement of the cam end 257 toward the platform pivot 252, the platform is free to descend under its own weight below the level of the conveyor belt 242, leaving the cartons on the belt.

A spring-biased actuator 260 riding below the surface of the conveyor belt is depressed when the conveyor belt is forced downward due to jamming of the carton in the carrier at the discharge station. A switch 261 operated by the actuator may suitably operate an alarm or shutdown circuit as desired.

Conveyor drive

The conveyor drive 40, as already mentioned, drives the several conveyor chains in timed synchronism with each other to provide the desired sequence of operations as explained in the preceding sections. Referring briefly to the drive arrangement, an electric motor 262 is coupled to gear box 263 to drive the main sprocket 264 at the desired speed. A main drive chain 265 extends around the main drive sprocket and sprockets in both the coating and cooling conveyors together with suitable idler sprockets. A secondary coupling chain 266 also couples the sprockets in both the coating and cooling conveyors. A rake sprocket 267 connected through a clutch to the rake gear 124 is driven through a rake chain 268 on a coating conveyor sprocket. Similarly, a sprocket 269 coupled to the infeed unit bevel gear 65 is coupled by a drive chain 270 to the coating conveyor sprockets. A transfer conveyor drive sprocket 271 is suitably coupled with an idler sprocket to a cooling conveyor sprocket. Other arrangements may be employed, of course, the particular one described being readily followed by reference to Fig. 1.

As previously brought out, the belt conveyors to the infeed unit and away from the discharge unit require no synchronism with the coating machine drive.

25 We claim:

1. In a machine for coating flat top paperboard cartons having overhanging top side edges and a hinged top flap, a first carrier having a top slide holder for suspending a carton by said edges with the top flap folded open, a first conveyor adapted to connect said carrier and carton suspended therefrom at a uniform rate in a closed circuit from a loading station to a transfer station through a tank of melted wax, loading means for sliding a carton into said loading station, drive means for said loading means coupled to said first conveyor to actuate the loading means as the carton slide holder is conveyed through said loading station, a second carrier having a top slide holder for suspending a carton by said side edges, a second conveyor for conveying said second carrier in a closed circuit through said transfer station, a cooling zone, and a discharge station, means for sliding cartons from said first conveyor carrier to said second conveyor carrier at said transfer station, and drive means for said second conveyor and said sliding means coupled to said first conveyor.

2. In a machine for coating flat top paperboard cartons having overhanging top side edges and a hinged top flap, a first conveyor for continuously conveying a series of spaced carrier bars in a closed circuit through a loading station, a tank containing melted wax, and a transfer station, a plurality of carriers on each of said bars each having a top slide holder for suspending a carton by said edges, means for sliding cartons into said holders with said top flap folded open, a second conveyor for continuously conveying a series of carrier bars in a closed circuit through said transfer station, a refrigerated zone, and a discharge station, a plurality of carriers on each of said second conveyor bars each having a top slide holder for suspending a carton by said edges, and means for transferring cartons from a first conveyor carrier to a second conveyor carrier at said transfer station, said transfer means including means for folding each carton top flap closed as the carton is transferred.

3. In a machine for coating flat top paperboard cartons having overhanging top side edges and a hinged top flap, a first conveyor for continuously conveying a series of spaced carrier bars in a closed circuit through a loading station, a tank containing melted wax, and a transfer station, a plurality of carriers on each of said bars, each carrier having a top slide holder for suspending a carton by said edges, means for sliding cartons into said holders with said top flap folded open, a second conveyor for continuously conveying a series of carrier bars in a closed circuit through said transfer station, a refrigerated zone, and a discharge station, a plurality of carriers on each of

said bars each having a top slide holder for suspending a carton by said edges, and means for transferring cartons from a first conveyor carrier to a second conveyor carrier at said transfer station.

4. In a carton conveying system for carrying flat top, lightweight paperboard cartons having overhanging top side edges, a carton hanger bracket having a pair of depending inwardly turned flanges spaced to accommodate the flat top of a carton between them, an upright first runner on each flange for supporting the lower surfaces of said overhanging top edges, a pair of downwardly extending spaced runners on each bracket for engaging the top surface of said carton and holding it against the first runners, means blocking one end of said hanger bracket, and opening closing means to accommodate loading of the hanger bracket with a carton at the other end of said hanger bracket comprising a lever pivotally connected to the top of the hanger with an overhanging portion blocking said other end.

5. In a carton conveying system for carrying flat top, lightweight paperboard cartons having overhanging top edges, a carton carrier bar having a hanger with a pair of depending inwardly turned side flanges for supporting the lower surfaces of said overhanging top edges, means closing the one end of said hanger, and releasable closing means at the carton entrance defined by the other end of said hanger comprising a lever pivotally connected to the top of the hanger having an end portion blocking said other end of the hanger, an operator member extending from said carrier bar for lifting said lever, means for conveying said bar past a transfer station, and cam means mounted at said station for lifting said operator member as the bar moves through the station to open the entrance end of said hanger.

6. In a conveying system for transferring light paperboard cartons having overhanging top side edges, a first carrier having a holder for slidably receiving the overhanging top side edges of a suspended carton, means for conveying said carrier to an unloading station, a second carrier having a holder for similarly receiving the overhanging side edges of a carton top, means for conveying the second holder to a loading station, a pair of spaced parallel guides extending between said loading and unloading stations for supporting the overhanging top side edges of cartons received between the guides, means at said unloading station for ejecting a carton from the first conveyor holder to a suspended position between said guides, and pusher means positioned for sliding an ejected carton along said guides from said first conveyor into the holder of said second conveyor.

7. In a wax coating machine for paperboard cartons having overhanging top side edges, a first conveyor having a holder for slidably receiving the overhanging top side edges of a suspended carton, means for cyclically conveying said holder with a carton suspended therefrom through a tank of melted wax and an unloading station, a second conveyor having a holder for similarly receiving the overhanging side edges of a carton top, means for cyclically conveying the second holder through a loading station and a refrigerator, a pair of spaced parallel guides extending between said loading and unloading stations for supporting the overhanging top side edges of cartons when dropped between the guides, stripping means at said unloading station for dropping the cartons from the first conveyor holder between said guides, and a transfer conveyor positioned below said first and second conveyors for sliding the ejected carton along said guides to overtake the

holder of said second conveyor being conveyed through the loading station.

8. In a conveying system for flat top lightweight paperboard cartons having overhanging top side edges, a carton carrier having a slide hanger closed at one end for receiving the top side edges of a carton, means for conveying the carrier downward with the carton suspended in a horizontal position, a horizontal conveyor belt positioned across the path of said carton, retaining bars positioned above the sides of the conveyor belt for stripping the carton from the hanger as the carrier descends below the bars, and means responsive to the further descent of said carrier to depress said bars and lower the carton onto the belt.

9. In a conveying system for flat top lightweight paperboard cartons having overhanging top side edges, a carton carrier having a slide hanger closed at one end for receiving the top side edges of a carton, a spring-biased gate for closing the other end of said hanger, means for

20 conveying the carrier downward with the carton suspended in a horizontal position, a moving conveyor belt positioned across the path of said carton, retaining bars positioned above the sides of the conveyor belt for lifting the carton from the hanger as the carrier descends below

25 the bars, cam means for opening the gate of said hanger as the hanger approaches the retaining bars, and additional cam means responsive to the further descent of said carrier to lower said bars below the conveyor belt.

10. In a machine for coating flat top paperboard cartons having overhanging top side edges and a hinged top flap, a carrier bar pivotally mounted between corresponding conveyor chains, a slide holder on said bar for suspending a carton by said edges with the top flap folded open, means for dragging said carrier with a carton suspended therefrom in a path through and up out of a tank of melted wax, and means for controlling the angular position of said pivoted carrier bar to direct the carton bottom ahead of the carton top along said path.

11. In a conveying system for flat top lightweight paperboard cartons having overhanging top side edges, a carrier bar pivotally mounted between corresponding points on a spaced pair of drive chain loops, means for driving said chain loops in a given path, a slide hanger on said bar for receiving the said side edges of a carton, and means for controlling the angular position of the carton said means comprising a main crank arm on the end of said bar, at least one auxiliary crank arm on said end of said bar angularly displaced with respect to said main crank arm, and cams positioned along a chain loop to selectively guide the crank ends to control the angular position of the bar.
